PAPER CUT-OFF AND FEEDING MECHANISM

Max Garbell, Chicago, Ill., assignor to Victor Adding Machine Company, Chicago, Ill., a corporation of Delaware

Application June 17, 1937, Serial No. 148,647

8 Claims. (Cl. 197—132)

This invention relates to improvements in adding machines, and has more particular relation to those, which, in addition to accumulating amounts in a totalizer, make a printed record of all transactions and issue a receipt for each transaction.

It is an object of the present invention to provide mechanism for severing a strip of paper after amounts recorded thereon have been totaled.

10 A further object is the provision of mechanism conditioned upon the total printing operation of the machine and released at near the completion of the operation for severing a paper strip which has amounts and the total of the transactions 15 printed thereon.

A further object is the provision of mechanism synchronized with the paper cut-off mechanism for effecting a step-by-step movement of the auxiliary paper strip after each printing operation of the machine and for effecting a greater movement to the paper and conditioning the paper cut-off means during the taking of the total printing operation.

20 A still further object is the provision of a paper cut-off mechanism positively conditioned at the will of the operator and automatically released at near the completion of operation of the machine for a spring-impelled severing action of the auxiliary paper strip and with rebound means coacting therewith, which serves to normally restore the cut-off means to its normal position after the severing operation.

25 Still a further object is the provision of feeding means for the auxiliary paper strip arranged to yieldingly engage the strip for feeding the same and to be manually separated to admit of the insertion of the strip.

30 And a further object is the provision of a cut-off mechanism which is arranged as a shear for severing the auxiliary paper strip.

35 Referring to the drawings, only so much of the machine is shown as is necessary for a clear understanding of the operation of the invention and its connections with the operative parts of the machine, and in which:

40 Figure 1 is a medial sectional view of the rear portion of the machine and carriage with my improved paper cut-off and feeding mechanism attached thereto.

45 Figure 2 is a medial sectional view similar to Figure 1, illustrating a changed position; and

50 Figure 3 is a detail plan sectional view taken substantially on the line 3—3 of Figure 1.

55 My improved mechanism is illustrated as being carried on the carriage of the adding machine.

and operatively connected for movement with the operating mechanism of the machine, and having manually controlled means for positioning the parts to condition the mechanism thereof for operation with the operating mechanism of the machine.

The machine herein disclosed comprises side walls 10 on which a carriage 11 is secured, and which carriage supports a platen 12 on a shaft 12a, a paper table 13, a record roll 14 and a feed 10 mechanism 15 for the strip R fed from the record roll.

A paper guide 16 serves to guide the record strip R around under the platen so that it will only engage the exposed front portion of the platen 15 adjacent the printing elements P and thence through a guide 18 to the feed mechanism 15.

As disclosed in the drawings, the feeding mechanism 15 is controlled by a pawl 19 which is pivoted at 20 on a rocker member 21 supported at 22 20 on the carriage 11. This rocker member 21 is operatively connected at 23 to a vertically disposed reciprocable member 24 guided in bearings 25—25 carried on the side wall 10 of the machine and this reciprocable member 24 is operatively connected to the actuator shaft 26 of the machine by means of a bell-crank 27 and a link 28. The rocker 21 is arranged to be rocked in a counterclockwise direction from Fig. 1 position to Fig. 2 position when the actuator shaft 26 is rocked forwardly, and in a clockwise direction while the actuator shaft is being restored. This movement of the rocker 21 upon the operating stroke of the actuator shaft 26 carries a feed pawl 29 into engagement with a ratchet wheel 30 fixed to the 30 platen 12 for feeding the same and for a ratcheting movement when restored. The feeding of the platen is independent of the feed of the record strip R and is solely for the purpose of positioning different portions of the platen in printing 40 position. When the rocker 21 is rocked in a counterclockwise direction, the pawl 19 will then engage to turn a ratchet wheel 31 to feed the record strip R and upon its restoring movement, it will ratchet thereagainst preparatory to the 45 next feeding operation.

My improved mechanism is arranged to be operatively connected with the rocker 21 and the reciprocable member 24 which causes its movements. This mechanism is arranged to normally 50 feed an auxiliary strip of paper A in uniform relation or the same distance as the record strip R is being fed during the normal printing operations of the machine. This auxiliary strip A is fed from a roll 32 carried on the side walls 10 of 55

the machine and directed through a trough 33 below the paper table or guide 16 and thence over the exposed portion of the record strip R adjacent the printing elements P and through a feed mechanism designated as a whole as 34 and over the paper table 13. The feed mechanism 34 comprises a roller 35 pivotally supported on the paper table 13 and a companion roller 36 pivotally supported at 37 on a plate 38 which is pivotally carried on the paper table 13 at 39, and which plate has springs 40 coacting therewith to normally urge the companion roller 36 into engagement with the roller 35. The plate 38 is provided with a pair of finger grips 41 to rock the plate on its pivot 39 with the companion roller 36 out of engagement with the roller 35 so as to insert the auxiliary paper strip A therebetween and to be gripped thereby when the plate 38 is released.

20 The roller 35 has a ratchet wheel 42 fixed thereto against which a pawl 43 is normally urged by means of a spring 44 and which pawl is carried at 45 on an arm 46 pivoted at 47 to the carriage 11. The arm 46 is in the form of a bell-crank having an integral downwardly directed portion 48 which is normally in the path of an ear 49 carried on the rocker 21, so that the movement of the rocker will effect movement of the bell-crank and pawl 43. A torsion spring 50 is carried by the pivot 47 and has one end engaging the arm 46 of the bell-crank and its other end engaging the carriage 11, so as to normally urge the arm 46 and pawl 43 upwardly, and the movement of the rocker member 21 with the ear 49 thereof away from the portion 48 of the arm 46 permits the spring 50 to carry the arm 46 and pawl 43 upwardly for a ratcheting action against the ratchet wheel 42. The restoring movement of the rocker member carries the ear 49 against 35 the portion 48 and effects a positive downward rocking movement of the arm 46 and pawl 43 to effect a turning movement of the ratchet wheel 42 and roller 35 to feed the auxiliary paper strip A.

45 During the upward movement of the reciprocal member 24 upon the forward stroke of the actuator shaft 26, the record strip R is fed and during the restoring movement of the reciprocal member 24 upon the restoring stroke of the actuator shaft, the auxiliary paper strip A is fed. The feeding of the record strip R and the auxiliary strip A is approximately the same distance and the cut-off mechanism and its operative parts including the manually controlled 50 means therefor conditions the feed means for the auxiliary strip A for a greater distance of movement than the distance it is fed during normal operations of the machine; and at which time, the severing means is conditioned and 55 brought into play so as to sever the auxiliary strip A.

The severing means is in the form of a shear comprising a swingable blade 51 which has one end thereof pivoted at 52 on a bracket 53 secured 60 to the paper table 13 and its other end is provided with a downwardly directed ear 54 to which a link 55 is pivoted at 56 and which link has its other end pivoted at 57 to a bell-crank 58 pivotally carried on the platen shaft 12a. The leg 65 58 of the bell-crank 58 carries a depending bell-crank member 60 pivotally connected thereto at 61 and the arm 60a of the bell-crank member is normally in the path of the leg 59 of the bell-crank 58 and serves to limit its movement to limit 70 the movement of the pawl 43 during a step-by-

step movement of the feed roller 35. The member 60 has a connecting link 62 at its free end and which link is connected to a bell-crank 63 carried at 64 on the side wall 10 of the machine. The bell-crank 63 extends into the path of a pin 65 carried by a depressible key 66 positioned in the keyboard of the machine, and which key is spring-urged to normal position. The key 66 is also arranged to be locked in depressed position and is provided with a notch 66a that coacts with 10 a slide 67 supported in a bearing 68 carried by the side wall 10 of the machine. The slide 67 has a spring 69 secured thereto and to a pin 70 carried by the side wall 10 and which spring 15 yieldingly retains an ear 67a of the slide 67 in sliding engagement with the key 66 preparatory to engaging a notch 66a therein. An arm 71 is pivoted at 72 to the slide 67 and is rockably supported on the side plate 10 at 73 with its lower end in the path of movement of a spring-urged 20 dog 74 carried on the link 28.

As thus far described, it will be noted that the depression of the key 66 (dotted lines Fig. 1), will cause a clockwise movement of the bell-crank 63 and a pull on the link 62 to swing the bell-crank member 60 forwardly on its pivot 61 without effecting movement of the bell-crank 58 on which it is carried. This swinging movement of the member 60 carries a lug 75 thereof under an ear 76 of a rockable member 77 pivotally carried at 78 on the side wall 10 of the machine, and which member has its other end operatively connected at 79 to the reciprocal member 24. When the machine is operated, the reciprocal member 24 will be carried upwardly by movement 30 of the bell-crank 27 and link 28 under the control of the actuator shaft 26, as above described, and this upward movement of the reciprocal member 24 will carry the pivot 79 upwardly therewith to rock the rockable member 77 on 40 its pivot 78 which rocks the ear 76 downwardly with the bell-crank member 60 therewith by reason of the engagement of the lug 75 thereof and ear 76. This downward movement of the bell-crank member 60 causes the bell-crank 58 to 45 rock in a clockwise direction on the platen shaft 12a, which through the link 55, carries the blade 51 for a rearward swinging movement on its pivot 52. This rocking movement of the bell-crank 58 carries an ear 80 formed on the leg 59 50 thereof into the path of a notch 81 provided in a dog 82 which is pivotally carried at 83 on the carriage 11, and which dog is urged toward the ear 80 by a spring 84 fixed thereto and to the carriage 11. The notch 81 of the dog 82 is then 55 urged over the ear 80 of the leg 59 of the bell-crank 58 to retain the same and bell-crank member 60 in the position to which they have been moved under the control of the rockable member 77 upon the movement of the reciprocal member 24. While the bell-crank 58 is retained in the position above described, the arm 60a of the bell-crank member 60 is carried out of the path of the leg 59 of the bell-crank 58 to permit of a greater movement of the bell-crank 58 and pawl 65 43 for a greater turning movement of the feed roller 35. At this time, the blade 51 is retained in its rearward position preparatory to severing the auxiliary strip A fed by the rollers 35 and 36.

During the restoring operation of the machine, 70 the bell-crank 58 is retained locked in position with the dog 82, and as the actuator shaft 26 is operatively connected with the depressible key 66, the dog 74 on the link 28 is carried into engagement with the arm 71 to rock the same 75

and move the slide 67 with the ear 67a thereof out of the notch 66a of the key 66 which permits the key to be spring-urged to normal position. When the key is released, the spring 85 restores the bell-crank member 60 with the lug 75 out of engagement with the ear 76 of the rockable member 77. When near the limit of its restoring movement, the ear 49 carries a portion 86 which is brought into engagement with the dog 82 to release the notch 81 thereof from the ear 80 of the leg 59 which releases the bell-crank 58 and permits it to be urged by a spring 87 fixed thereto and to the carriage 11. This movement of the bell-crank 58 carries the blade 51 therewith for a swinging movement on its pivot 52 and with the cutting edge 51a of the blade over a companion edge 88 secured to the paper table 13.

In order to maintain a constant tension on the blade 51, a spring 89 is arranged to engage the top surface thereof and which spring is carried on a pin 90 that is pivotally supported at 91 on the paper table 13, and which pin has its other end extending through an opening 92 in the blade 51. This spring 89 serves to retain the blade in engagement with a shelf 93 carried by the paper table and which shelf is provided with a slot 94 to permit the pin 90 to extend through the blade 51 and to freely ride within the slot. This tension of the spring 89 serves to retain the cutting edge 51a of the blade for engagement with the companion edge 88 secured to the paper table 13.

It will be noted that the leg 59 of the bell-crank 58 has a relatively light tension spring 95 secured to the underneath edge thereof and which spring has its other end anchored to the carriage and serves as a restoring spring to restore the bell-crank 58 after the bell-crank and blade 51 have been released to sever the auxiliary strip A under the control of the spring 87. This relatively light tension spring 95 is of just sufficient tension to retain the bell-crank 58 and blade 51 in its normal position while the spring 87 is in its normal position.

I claim:

1. In a paper cut-off and feeding mechanism for an adding machine or the like comprising feeding means arranged to feed a paper strip upon one operation of the machine and severing means for the paper strip adapted to be conditioned upon said operation, manually manipulative means conditioning said severing means for severing operations, said manually manipulative means serving also to condition said feed means for a greater distance of feed while conditioning the severing means, said severing means when conditioned being releasable at near the restoring operation of the machine for effecting a severing movement of said severing means.

2. In an adding machine or the like having two paper strips arranged to have like impressions simultaneously printed thereon, of means for severing one of said strips comprising, shear means having operative connections therefor arranged to be operatively controlled upon the operating movement of the machine and normally disengaged therefrom, of manipulative means operatively connected with said operative connections for effecting engagement thereof with the operative connections of the machine, said operative connections of the severing means being releasable at near the completion of operation of the machine, and means connected with said severing means yieldingly urging the same for severing operations and carrying said severing means to sever the paper when said operative

connections thereof are released from the operative connections of the machine.

3. In a machine of the character described having a record strip and feed means therefor, of an auxiliary strip fed in printing relation with said record strip, feed means and severing mechanism for said auxiliary strip, said feed means being operable for a normal feed of the auxiliary paper strip and to selectively feed said strip a distance greater than its normal feed, said feed means and severing mechanism being arranged to be conditioned for operation with the operative connections of the machine, and manipulative means for conditioning the feed means and severing mechanism with the operative connections of the machine whereby during the completion of operation of the machine the auxiliary strip will be fed a greater distance and thereafter severed.

4. In a machine of the character described having a record strip and feed means therefor, of an auxiliary strip fed in printing relation with said record strip including feed means and severing mechanism therefor, and connections from said feeding means and severing mechanism arranged to be actuated by the operative connections of the machine, and manually manipulative means for conditioning said connections with the operative connections of the machine whereby said connections will effect a feed of and sever the auxiliary strip at near the completion of operation of the machine and whereby said connections will be released from the operative connections of the machine and restored to normal positions.

5. The combination of claim 4 hereof in which said manually manipulative means controls the feeding means for a greater distance of movement to effect a greater distance of feed to the auxiliary strip prior to the severing operation of the severing mechanism.

6. In a paper cut-off and feeding mechanism for an adding machine or the like comprising feeding means for a paper strip arranged to feed said strip a given distance upon normal operations of the machine and to selectively feed the strip a distance greater than the normal feed, severing means adapted to be conditioned upon and released after the strip has been fed a greater distance, manipulative means serving to condition said feed means for a greater distance of feed while conditioning the severing means for a severing movement, said severing means when conditioned being releasable at near the restoring operation of the machine for severing the strip.

7. In an adding machine or the like having two paper strips arranged to be fed a like distance and to simultaneously receive like impressions thereon, of means for increasing the feed and for severing one of said strips comprising, feed means having operative connections therefor arranged to be actuated upon the operating movement of the machine, spring-urged shear means having operative connections normally disengaged from the operative connections of the machine, of manipulative means for effecting engagement of the operative connections of the shear means with the operative connections of the machine, said shear means being movable with the operative connections of the machine when conditioned by said manipulative means, said shear means being retained against the tension of its spring when moved by the operative connections of the machine, and means at near

the restoring movement of said operative connections effecting the release of said shear means for a spring-urged movement thereof to shear the strip.

- 5 8. In a paper cut-off and feeding mechanism for an adding machine or the like, a paper table, feeding means mounted thereon and connected to the operative connections of the machine and arranged to feed the paper a given distance and
10 to selectively feed the paper a greater distance,

severing means adapted to be conditioned to sever the paper during the greater distance of movement of the paper, manipulative means for conditioning said feed means for a greater distance of movement and for conditioning the severing means for a severing movement, and means effecting the release of said severing means after the paper has been fed a greater distance.

MAX GARBELL. 10
